ENGINE BED UNDERFRAME

Earl J. W. Ragsdale, Norristown, and Albert G. Dean, Narberth, Pa., assignors to Edward G. Budd Manufacturing Company, Philadelphia, Pa., a corporation of Pennsylvania

Application April 13, 1936, Serial No. 74,134
Renewed June 21, 1939

21 Claims. (Cl. 105—414)

This invention relates to improvements in underframe construction for rail cars and more particularly to an improved underframe for a tractor unit rail car having integral power plant supporting elements. It is a continuation in part of co-pending application Serial Number 720,490 filed April 13, 1934 and entitled "Rail car front end construction".

The development of high speed, light weight rail car construction especially adapted for self-contained power plants as of the Diesel type has required an economy of weight as well as an increase in strength and safety. The horsepower required depends on the weight of the car and an increase in power plant requirements involves a further increase in weight. If the allowable loading limit on double truck axles is reached, however, more axles involving further weight are necessary. Highly efficient stressing of the effective parts of the underframe is thus of major importance in the high speed, light weight rail car service.

Furthermore, at the high speeds at which these rail cars are adapted to run, the collision reacting force is greater rather than less as would be expected with the lighter weight trains, inasmuch as the collision reaction depends on the second power of the speed. It is essential that the underframe be of even greater strength than the prior heavy structures used, and it must be of lighter weight than prior constructions in order to economize on power demands.

One of the principal objects of this invention is to provide a combined underframe and power plant support which extends substantially throughout the forepart of a tractor unit rail car and serves to carry the entire body as well as the power plant, the load reactions being transmitted through an integral bolster to the supporting truck.

Another object of the invention is to provide a combined underframe and power plant supporting structure for a light weight, truss type car in which the power plant and underframe is balanced over the integral bolster so that the car body is normally free of power plant load reactions, thus insuring steadier operation and greater traction.

Another and more specific object of the invention is to provide a combined underframe and power plant supporting structure for a rail car having substantially through running longitudinal web truss members for directly taking the possible collision stresses and acting as the principal longitudinal sills for strengthening

the underframe and simultaneously supporting the power plant.

Another object of the invention is to provide a welded plate structure of a high strength metal alloy for a power plant bed which can be arc welded at the respective seams and built into an open, cellular structure of great strength and rigidity and which is simultaneously adapted for supporting a light weight truss type rail car body of a high speed rail car tractor unit.

A still further object of the invention is to provide a unitary power plant support and underframe structure having forwardly projecting bumper portions and rearwardly extending stress distributing members for the adequate reaction to collision loads, distribution of collision loads on the body to the underframe and side frames, and balancing out bending moment reactions into the body side frames.

Another object of the invention is to provide a power plant supporting base structure to which the main portion of the body of the rail car may be secured, such base in itself serving as the flooring of the power plant compartment, and having a rounded front end to take and ward off laterally collision shocks, such base having draft gear receiving pockets and being adapted to anchor body beams of an anti-collision nature to prevent shearing off in case of accident.

Further objects and advantages of the invention will appear from the following description of preferred forms of embodiment thereof as shown on the attached drawings in which:

Fig. 1 is a side elevation, with parts in section of the front end of a rail car showing the construction and location of the combined power plant support and car body underframe.

Fig. 2 is a perspective view of the underframe shown in Fig. 1.

Fig. 3 is a top plan view of the underframe shown in Fig. 1 and at a slightly smaller scale.

Fig. 4 is a vertical section through the body side frame and a part of the underframe showing the manner of attachment of the side frames thereto.

Fig. 5 is a top plan view of a modified form of underframe and power plant support construction.

Fig. 6 is a side elevation of the construction shown in Fig. 5.

Figs. 7 to 18 inclusive are vertical sections taken along the lines 7—7 to 18—18 respectively on Fig. 5.

In accordance with our invention, a rail car

tractor unit 10 as generally shown in Fig. 1 is mounted on a unitary member 11 which constitutes a combined underframe and power plant support. This underframe and power plant support member 11 is preferably mounted in balanced relation to the truck 12 by the relatively large annular truck bearing 13 on the truck frame, the king pin bolt 14 passing through this bearing and the bolster, thus tying the underframe to the truck while permitting a relative rotation therebetween.

When the remaining part of the car is used for baggage or passenger accommodation, an extremely light weight truss construction for the body may be used, and in such case the underframe extends only under the forward portion of the car over the supporting truck. Preferably, the underframe extends substantially throughout the operator's compartment and power plant compartment to the bulkhead 10a, thus serving not only as the power plant support but also as the entire underframe for the body in this region, and as described hereinafter, the body framework is secured thereto. If, however, the entire car were to be used for power plant, the underframe would extend throughout the car. The light weight truss type body construction for baggage or passenger accommodation does not require a through running underframe of this type, however.

The underframe and power plant support member 11 is provided centrally with longitudinally extending raised beams 15 of web truss construction, which are tied together transversely 35 and reinforced by top flanges 16 forming top chord members of the truss. The main unit of the power plant generally indicated at 17 in Fig. 1 is secured to these top flanges. The power plant, which in the preferred construction includes an internal combustion engine, which may be of the Diesel type, and generator, is so disposed longitudinally and transversely of the underframe that the combined weight of power plant and underframe and the principal accessories is substantially balanced over the king pin 40 14. This location of the center of gravity of the underframe 11 and the power plant and its principal accessories substantially directly over the king pin, insures minimum reactions between truck and body in rounding a curve and greatly improves the smoothness of operation. The weight is evenly distributed on the driving wheels and by reason of this mass being directly over the driving truck, better traction is had.

The front portion 11a of the underframe structure becomes one of the principal transverse members and in front is slightly offset downwardly and conveniently forms the flooring for the operator's compartment 19. Large openings materially reduce the weight of this part of the underframe. A pocket or pockets 11b opening toward the front are adapted to house the draft gear and buffer connections. The front end 11a of the underframe 11 is rounded on a 65 relatively short radius of curvature similar to the contour of the body front, and acts to take collision shocks directly and with the body tends to ward off laterally any solid objects in its path. It is continuous with the ends of longitudinal sills 15 and is welded thereto. Side plates 25 serve as anchorages for the body side frames.

At the central portion of its front, the underframe carries a rearwardly and upwardly inclined collision beam 24 extending substantially 75 to the roof, and the upper end of this beam ties

into the roof framing and braces the underframe directly to the roof. A socket 24a, formed on the underframe, is provided to prevent shearing of the collision beam at the underframe.

Intermediate the length of the underframe 11 is an integral bolster 20, and at its sides the bolster is provided with vertically relatively deep side plates 21 formed with outwardly extending flanges 22 approximately equal to the thickness of the body side wall framing and forming assembly joint structures by which the body side walls are secured to the underframe. The downwardly extending portions of plates 21 are preferably braced through brackets 23 to the bottom wall of the bolster, see Fig. 4.

The vertical side frame post carlines 30 are secured to the underframe 11 and interconnected to each other by a deep vertical plate 32 corresponding to the depth of the side plates 21 of the underframe. The plate 32 is inwardly flanged in 20 its top margin at 33 and in the final assembly nests with the angle formed by the flooring of the underframe and the side plate 21 and is rigidly secured thereto substantially throughout the length of the underframe as indicated by the 25 rivets 34. By this construction, a very rigid and strong interconnection between the unitary underframe and the light weight side wall trusses of the body is attained.

The underframe which serves double duty as 30 the supporting structure for the remainder of the car and as the power plant support consists essentially of a series of relatively wide and thin plates welded to vertical webs to make an internal cellular and rigid structure. Such a construction is preferably made of a plurality of 35 separately welded plates due to the extreme lightness possible, although it is of course to be understood that the plates may be riveted with only a slight increase of weight and without material sacrifice of strength, but welding is preferable.

To the rear of the bolster 20 and acting as a needle beam, is an open web-like member 26 of generally outwardly diverging triangular like 45 sections by which longitudinal stresses of the body are transferred to the longitudinal power plant supports of the underframe and thence to the supporting truck. The side post joining plates 32 are also secured to this portion of the 50 underframe. With such a construction a center sill is not essential and thereby great reductions can be had in the gross weight of the rail car.

Between the longitudinal sills 15 are a plurality 55 of vertical webs 27 integral with the underframe webs and of a suitable shape to permit adequate clearance between the underframe and power plant. A horizontal web 28 may also be used between the webs adjacent the bottoms of the longitudinal sills and it may be cut out for weight reduction or convenience to provide holes as desired.

The longitudinal sills also may have suitable 65 hand holes 29 to facilitate attachment of the power plant and to facilitate welding. In addition these holes tend to lighten the structure.

It is to be noted that the flanges 16 serving as the top chords, bottom plates and flanges 28 and 15a serving as lower chords, and intermediate webs 15 with frequent vertical stiffeners including inside webs 27 and outside columns 31, constitute the entire underframe a truss and by using the top chords as engine supports, webs as generator supports, and bottom chord ex- 75

tensions as floor supports, the underframe becomes an integral, efficiently stressed part of the tractor unit body without any unnecessary duplication of parts or unnecessary weight. It adequately accomplishes its principal mission of supporting the power plant, and in addition it eliminates the usual car underframe in the forward part of the car and makes it unnecessary in the remaining part of the car.

It will thus be seen that the entire underframe acts as the car body supporting medium, permits adequate stress transmission with the light weight truss type body framing and forms the principal strength member both for the underframe as well as the power plant support. Plates are used in general with adequate fillets where strength is needed, and they are readily formed into box sections by welding.

A modified construction is generally represented at 40 in Fig. 5 and is also preferably made of a plurality of plates joined into a unitary structure as by welding, and similarly has longitudinal power plant supporting flanges 41, which as shown in Fig. 6, extend from deep webs 41a. This pair of longitudinal web and flange members constitute a truss, as in the first form of embodiment of the invention, and reenforce the underframe throughout its length, such longitudinal members having flanges 41 of reduced width forwardly of the bolster 43 for receiving the generator of the power plant, not shown. The bottom of the underframe, between longitudinal web members 41a, is covered by a plate 44 covering the entire bottom, as shown in Fig. 14, which has hand holes 46 for adjustment of the power plant.

In this embodiment of the invention the longitudinal sills 41 extend not only to the rear needle beam 50 but to the end tie member 51, below which they are then secured to the center sill members, not shown. The plate 44 preferably extends back to this point, although if desired it may be terminated at the needle beam 50. Diagonal members 66 facilitate transmission of the stresses from the underframe to the relatively deep side plates 68 at the needle beam, which side plate is adapted to be secured to a plate attached to the relatively thin section posts of the body as in the previously mentioned construction. A transverse section through the web 41a is shown in Fig. 17, the plate 44 joining the bottom chord flange members 96.

Transverse sections through the underframe in the generator receiving compartment are generally shown in Figs. 12 and 14. Fig. 12, taken along the line 12—12 of Fig. 5, shows the fabricated web type of transverse reinforcement near the front of the underframe and forward of the generator. The main web 41a having the flange 41 is formed into a box section on the inside by a plate 85 becoming a flange extension and an inside vertical plate 86, which in the center of the underframe becomes of arcuate shape in plan view and extends from side to side for a center reinforcement. Here again hand holes 87 are provided to facilitate welding of the respective sides of the joint. Fig. 14, however, is a transverse vertical section entirely across the underframe and to the rear of Fig. 12, and shows generator supporting brackets 92.

The transverse members in this construction include the bolster 43, which is substantially centered in the underframe unit and is provided with the deep side plates 48 as shown in Fig. 6. Forwardly of the bolster and spaced therefrom is the

forward transverse member 49, while a needle beam 50 is provided rearward of the bolster. A final junction channel 51 is also provided to aid in tying in the side frames.

The front sill member 49 is provided with a bumper portion 55 of generally rounded configuration, having relatively large openings 56 to facilitate fabrication and to reduce weight. Intermediate of this bumper portion 55 is a substantially triangular plate 57 which is supported by vertical web members 58 which are joined in an effective triangular shape and have their apex approximately at point 59 rearward of the collision beam receiving socket 60.

The webs 58 extend from regions adjacent the ends of the longitudinal sills 41a, although they are in the stepped down region of the bumper portion 55. A cross section of the channel shaped bumper portion 55 and of the hollow box collision resisting section 55a is shown in Fig. 7. It is, of course, to be understood that if desired the webs 58 might extend directly forward of the bumper portion 55 in a substantially parallel relation, and where it is necessary to use the space above the bumper portion for structural reasons, such as for air intake or other purpose, the parallel construction may be preferred.

Transverse views through the front sill 49 are shown in Figs. 13 and 15. Fig. 13 shows the web 88 as the principal element, such web having a plate 89 and a flange 90 which presents rearwardly, and a bottom flange 91 serving to reenforce the front sill member. In Fig. 15, it will be noted that the plate 57 covers the triangular framework and the web 88. A bracket 95 serves to support the pilot to the underframe and a reinforcing web 96 projects down from a plate 57 for additional reenforcement. The rear part of plate 57 becomes plate 85 and the bottom plate 44 between the sills extends into vertical plate 88.

The bolster is shown in cross section in Fig. 8 and has the relatively deep side plates 70 having the bottom plate supporting flanges 70a and the relatively heavy top and bottom bolster plates 71 and 72 which extend entirely across the underframe from side to side. The longitudinal sill webs 41a support the engine receiving flanges at 41, such sill web being substantially continuous from one flange 41 down the side 41a, intermediate web 41b, across the bottom web 41c, up the other side to the other flange. The king pin post 72 extends down to the bottom web 41c and is thus reenforced for its reaction with the truck. Side bearings 73 cooperate with appropriate portions of the truck as will be understood. The bottom extension of the side plate 70 is preferably joined by a reinforcing web 75 to the lower bolster plate 72.

Transversely, the bolster consists of a plurality of webs as more clearly shown in Figs. 10 and 11. Fig. 10 is a section taken transverse of the bolster on the line 10—10 of Fig. 5, and the plurality of webs 76, 77 and 78 of which the bolster is made, join the top plate 71 having openings 80 and bottom plate 72. Supplementary webs 79 are provided on the outside of the main bolster. It will be noted from Fig. 11, which is taken between the webs 41a, that the box construction of the bolster is continued from end to end thereof, and throughout the center portion, additional reinforcement is provided by plate 41c for the king pin support, the plate 41c having transverse edge flanges 41d.

Details of the needle beam 50 are shown in Fig. 9. The needle beam is a comparatively shallow

beam on each side of the longitudinal s webs 41a and 41b, although the deep transvers 5 vertical web 82 between the sills acts as a central reinforcing extension of it. The ends of the needle beam 50 terminate in large plates 68, heretofore mentioned, for adequate joinder with the side post joining plate, not shown. It will be noted that the flanges 41 recede from the top plane to the bottom of the underframe structure, being 10 continuous and thus completing the longitudinal truss. In Fig. 18, the needle beam is shown in transverse section and includes top flange 98, web 99, and plate 44.

The underframe is readily constructed into a 15 rigid unitary structure by welding although composed of plates, and plates can readily be cut to give the necessary strength with the minimum of weight. It is especially suitable for rail car operation, for power plant loads can be accurately 20 balanced without danger of structural failure and without imposing unnecessary loads on the car body.

While we have shown preferred forms of embodiment of the invention, we are aware that 25 changes can be made, and we thus desire a broad interpretation of our invention within the scope and spirit of the disclosure herein and of the claims appended hereinafter.

What we claim is:

- 30 1. An integral front end underframe for a rail car which comprises shallow cellular bumper, bolster, and needle beam elements and longitudinally extending and upwardly projecting web sill elements tying said shallow cellular elements together and supporting an engine and generator thereon, said web sill elements being of substantially I-section, the top flange of which is a top chord of a truss, said underframe consisting of a plurality of plates welded together.
- 25 2. A one piece fabricated plate rail car underframe of arc welded construction having a relatively deep pair of longitudinal webs constituting principal strength members of the underframe, and transversely extending bolster and needle beam members, the longitudinal webs having topmost plate flanges for securing a power plant thereto and longitudinally spaced transverse body securing extensions, said longitudinal webs to the rear of said extensions being adapted for 35 attachment to a main car frame, and brace members extending from the longitudinal webs of the power plant supports to the side of the underframe adjacent the ends of the needle beam member for transmitting a portion of the longitudinal stresses to the main car frame.
- 40 3. A rail car underframe having formed integrally therewith a front sill, bumper, bolster, and needle beam, each of which act as direct supports of a car body, and each of which consists of at least one vertical plate and top and bottom plates welded thereto to form truss structures, and means to join said front sill, bumper, bolster and needle beams, said joining means including power plant supporting means 45 including webs and chords welded together at their abutting portions and forming parts of longitudinal trusses.

4. An integral car underframe structure for the front end of a self-propelled car body comprising a bolster, longitudinal sills, flanges on said sills on opposite sides of said bolster for supporting a power plant, a bumper on one side of said bolster, and a needle beam on the other side of the bolster, and means on said bolster, bumper and needle beam to support a car body,

said underframe having its center of gravity substantially over the bolster.

5. In a self-propelled rail car an underframe comprising a pair of longitudinal sills of separate plate flange and plate web construction including flanged floor supports, the top plate flange on said sills providing supports for an engine located above the level of said floor supports, said sills extending to a bumper portion forwardly of said engine supports, socket means to support a body collision resisting beam on said bumper portion against longitudinal shear loads, and braces diverging from said socket means to connect with said sills whereby to distribute collision loads on said beam directly into said sills. 10

6. A rail car tractor unit underframe which comprises a relatively wide shallow box type plate bolster, a relatively deep transverse member forward of the bolster and spaced therefrom, a transverse needle beam rearward of the bolster, 20 said transverse members having relatively deep aligned side plates whereby a truss type body may be secured thereto, and longitudinal truss type power plant supports joining said spaced transverse members. 25

7. A rail car tractor unit underframe which comprises a relatively wide, shallow box type plate bolster, a plurality of transverse members on the respective sides and spaced from said bolster, said bolster and transverse members 30 having relatively deep side plates on the respective ends thereof whereby a truss type body may be secured thereto, longitudinal truss type power plant supports joining said spaced transverse members, and a plate joining the longitudinal 35 power plant supports substantially near the bottom thereof.

8. A rail car tractor unit underframe including a central transverse bolster, continuous longitudinal truss type power plant supports having 40 plate webs and plate chords extending on each side of said bolster, a forwardly projecting transverse bumper portion integral with said power plant supports, and a transverse needle beam rearwardly of said bolster and integral with said 45 supports, said bolster being the balancing point of the underframe and its power plant.

9. A tractor unit combined unitary power plant support and front end underframe for light weight rail car construction in which relatively high tractive effort is required which includes a bolster, longitudinal power plant supports of truss type having plate webs and plate chords to which the power plant is secured, and transversely extending beam members at the 55 opposite extremities of the power plant supports and spaced respectively in front and in rear of the bolster, said beams extending laterally for attachment to the car body, said supports forming a stiffening portion of the underframe, and being so located that the center of gravity of 60 the power plant and underframe is substantially over the bolster.

10. An integral car underframe structure comprising longitudinal sill truss members, a bolster 65 having a top plate member serving as a top chord and extending through said truss members, said truss members having continuous top plates welded thereto and extending on opposite sides of said bolster to support an engine and generator respectively, said engine supporting means being the top chords of said longitudinal sill truss members. 70

11. An integral front end underframe for a rail car having a self contained power plant which 75

- comprises a front sill and bumper portion, an intermediate bolster adapted to be supported from a truck and a rear needle beam, said rear needle beam being spaced aft of the bolster substantially as much as the front sill is forward thereof for a balance of the underframe over the bolster, said bolster, front sill and bumper portion, and rear needle beam being adapted to receive and support parts of a car body, and longitudinal vertically stiffened plate truss members extending between said front sill and bumper portion and said needle beam and above said bolster, said longitudinal truss members having power plant supports welded thereon, said supports being continuous from needle beam to front sill. 5
12. A car underframe and power plant support structure comprising a plurality of longitudinally extending I-section truss members having power plant supporting flange upper chords, transverse webs and vertical reinforcing members forming posts and I-section lower chord members, all of which are formed of plate members welded to form an integral unit, and additional means to join the truss members including a plate approximately at the bottom chord, and means to support said underframe intermediate its ends, said means including a reinforced box section bolster beam having continuous chord members extending to body attaching side plates. 10
13. A rail car power plant supporting structure, comprising longitudinal truss members including top chords, bottom chords and webs therebetween, a front end sill, a stepped down front portion adapted to support an operator's compartment and having an outwardly projecting bumper element of generally rounded shape and tied into said front end sill on each edge and in the middle, and a rear portion approximately at the level of the bottom chord member to which the car body is adapted to be secured, the bottom chord member extending throughout the length of the supporting structure and having a transverse plate extending between the longitudinal truss members. 15
14. A rail car power plant supporting structure, comprising longitudinal truss members including top chords, bottom chords and webs therebetween, a stepped down front portion adapted to support an operator's compartment, and a rear portion approximately at the level of the bottom chord member to which the car body is adapted to be secured, said bottom chord member extending throughout the length of the supporting structure and having a transverse plate extending between the longitudinal truss members, said top chords directly supporting the power plant, means to tie in the top chords with the front portion and rear portion, and means joining the trusses including a plurality of webs. 20
15. A rail car underframe for a self-propelled light-weight truss type body, said underframe having longitudinally extending power plant supporting webs, and chord members, said webs and chords consisting of mutually welded plates constituting portions of principal load supporting trusses, said chords having portions to support a power plant including engine and generator, and an integral box section arc welded plate bolster having a top chord continuous through and welded to the power plant supporting webs, said bolster having reinforcing means to mount said underframe over a supporting truck. 25
16. A rail car tractor unit underframe which comprises a relatively wide shallow box type plate bolster having relatively deep side body securing plates on the respective ends thereof, inner and outer transverse members extending continuously across said underframe and spaced from said bolster, means to secure the main car frame to the ends of said transverse members and bolster, longitudinal truss type power plant supports joining said spaced transverse members, and brace means extending from said longitudinal supports in the region of the inner transverse member rearwardly and outwardly to the main car frame to distribute a portion of longitudinal collision stresses to the main car frame. 30
17. A rail car tractor unit underframe of plate elements fabricated into a hollow cellular structure and having longitudinal sills of relatively deep I-section extending substantially the full length of the frame, and including flanges welded to the webs of said sills and constituting each a top chord of a truss and supporting a power plant, transverse members including a bolster projecting from the sides of said longitudinal members and having relatively deep surfaces at the ends thereof in substantial longitudinal alignment with each other for attachment of a truss type of car body, certain transverse members being substantially equally spaced fore and aft of the bolster and an integral horizontal web joining lower portions of the respective longitudinal members, the forward transverse member including a bumper of a generally rounded hollow plate construction having a central longitudinal web substantially intermediate of the first mentioned longitudinal members. 35
18. In a rail car, a unitary underframe comprising an engine base and a forwardly extended bumper portion transversely rounded at its forward edge and having its top face generally at a lower level than the engine base portion rearwardly thereof, an integral socket at the forward central portion of said bumper portion to receive the lower end of a collision beam, and a triangular integral brace extending rearwardly from said socket to the raised engine bed portion of the underframe. 40
19. In a rail car, a unitary underframe comprising an engine base and having a forwardly extended bumper portion transversely rounded at its forward edge and having its top face generally at a lower level than the engine base rearwardly thereof, an integral socket at the forward central portion of said bumper portion to receive the lower end of a collision beam, and an integral brace extending rearwardly from said socket to the raised engine bed portion of the underframe. 45
20. A combined power plant support and underframe structure for a self-propelled rail car which comprises a body portion having longitudinally extending vertical webs for receiving a power plant, a front sill member tied in with the top and bottom of said vertical webs and supported thereby, a bumper portion forward of said end sill member, said bumper portion being of generally semi-circular shape in plan with the ends tied in with the ends of the front sill member, said bumper portion being adapted to integrally receive body structure posts and a triangular raised portion within said bumper portion extending from the foremost portion of the effective extremities of the vertical power plant 50
- 55
- 60
- 65
- 70
- 75

supporting webs to an apex at the fore part of the bumper portion, said raised portion providing a very high shear resisting support for a foremost body member.

5 21. A rail car underframe mounted at the front on a truck and including a unitary member extending from the front of the car to some distance in rear of the truck and constituting the power plant support and transverse body bolster

over the truck, the whole supported in balanced relation over the truck, said member having vertically deep side portions in front adjacent the bolster and also a substantial distance to the rear of said bolster for tying into the side walls 5 of the body.

EARL J. W. RAGSDALE.
ALBERT G. DEAN.
